MOP WRINGER

William F. Blake, South Pasadena, Calif., assignor, by mesne assignments, to Frederick A. Speik, South Pasadena, Calif.

Application April 27, 1934, Serial No. 722,745

1 Claim. (Cl. 15—262)

The invention relates to improvements in mop wringers in which two wringer rolls, one flexible and adjustable, are used in connection with a pedal lever; and the objects of the invention are first, to provide a light weight mop wringer and one that is easy to operate, second, to provide a wringer that needs only one foot, not two, to operate it, and, third, to provide a wringer that will wring a mop dry.

This invention will be readily understood from the following description and claim, and from the drawings, in which Figure 1 is a view of mop wringer; Figure 2, a plan view of the floor brace; Figure 3, a vertical elevation of the brace shown in Figure 2; Figure 4, a view of the mop guide and roller; Figure 5, a detail view of the guide; Figure 6, an end view of the guide and roller; Figure 7 is a side elevation with the top broken away to show the operation of the wringer rolls; Figure 8, a detail view of the flexible and adjustable roll; and Figure 9, a detail view of the adjustable and flexible feature of the wringer roll.

In Fig. 1 is shown the oblong mop bucket 1 with the floor brace 2, having the projection 3 extending outward to make a positive brace against the bucket tipping over when in use. At the outer edge of the projection 3 is the rubber cushion 4 to prevent the wringer from movement or from making a noise when in use.

In Fig. 4 is shown the angular mop guide and bearing 5 with the wringer roll 8 journaled therein by the journal 6. The roll 8 is rotatable but always in the same position at the front of the mop bucket. The flange 7 projects inwardly and is below the roll 8, as shown in Fig. 6, thus serving as a reducing guide to the mop cloth.

In Fig. 7 is shown the foot pedal 9 with the projection 10 of the same shape but smaller than the projection 3 of the floor brace 2. The foot pedal 9 is journaled to the sides of the bucket 1 with the screws 11 and the springs 12 are inserted between the pedal 9 and the bail support 13 to keep the foot pedal 9 in the position shown in Fig. 1 when not in use.

At the opposite end of the foot pedal 9 is the hanger 14 carrying the wringer roll 15. This roll, as also the roll 8, is much smaller at center 16 than at the ends where it is attached to hanger 14 by the journal 17, as shown in Fig. 8. The rubber cushions 18 are put around the hanger 14 to keep it from making a clatter when it comes in contact with and is stopped by the sides of the bucket 1, see Figures 7 and 8. In

Fig. 9 is shown the construction of the adjustable roll 15. In the hanger 14 there is the slot 19 for the journal 17 to rest in and back of the journal 17 is the coil spring 20 resting against the thumb screw 21 by which the tension between the journal 17 and the coil spring 20 can be regulated. By this means when pressure is applied to the wringer roll 15 as in wringing out a mop, the roll can move back a little when necessary but instantly when the knot or fold in the cloth is past, the pressure of spring 20 forces the roll 15 back into close proximity with the mop cloth.

The bail 22, having the handle 23, is fastened to the bail support 13 by the screw 24 and around this screw is a spring 25. This spring 25 always keeps the bail 22 on the front of the bucket 1 and therefore out of the way of the mop being placed between the rolls 8 and 15.

In the practical operation of my invention, the bucket 1 is half filled, or just a little above the journal 11, and is carried to wherever the mopping is to be done by the bail 22. When placed on the floor and the hand removed from the bail 22, the bail immediately falls to rest on the front of the bucket 1 because of the spring 25. The mop is placed in the bucket between the rolls 8 and 15 in the water or soapsuds and used as any mop is. When it is desired to wring the mop it is lifted up until the top of the mop cloth rests on the guides 7, thus the mop cloth is kept from spreading out, and then one foot is placed on the projection 10 of the foot pedal 9 which is pressed down until projection 10 rests on projection 3 of the floor brace 2, this brings the hanger 14 and the roll 15 forward until it is in close contact with roll 8 and guides 7 with the mop cloth between the rolls. The special shape of the two rolls allows the heavy part of the mop cloth that is the center and the thinner edges to receive the same amount of pressure. With the rolls held in contact as described above, the mop handle is grasped by the hands and pulled upward and out from the rolls thus pressing out the water. The spring tension at the back of roll 15 supplies different degrees of pressure varying as the thickness of the mop varies. When the foot is removed from projection 10 the foot pedal 9 immediately returns to the position shown in Fig. 1 because of the spring 12. The rubber cushion 4 prevents clatter on the floor and also prevents movement of the mop wringer when pressure is placed on the foot brace and this construction also prevents tipping of the bucket. The rubber cushions 18 prevent

clatter on the edges of the bucket when the roll is returned to its open position. My mop wringer is light in weight and can be operated easily and is exceedingly effective.

5 What I claim is:

In a mop wringer, a bucket, plates secured on the sides of said bucket, a wringing roll carrying frame pivotally mounted on said plates, springs

arranged between said plates and said frame and yieldingly resisting the movement of said frame in one direction, a bail pivotally connected to the upper ends of said plates and springs arranged between said plates and bail for yieldingly resisting swinging movement of the bail in one direction. 5

WILLIAM F. BLAKE.
